DESIGN FOR A COMBINED OIL BURNER CASING AND SUPPORT THEREFOR

Malcolm R. Knox, Hartford, Conn., assignor to
The Silent Glow Oil Burner Corporation, Hartford, Conn., a corporation of Connecticut

Application January 3, 1936, Serial No. 60,403
Term of patent 14 years

To all whom it may concern:

Be it known that I, Malcolm R. Knox, a citizen of the United States, residing at Hartford, county of Hartford, and State of Connecticut, have invented a new, original, and ornamental Design for a Combined Oil Burner Casing and Support Therefor, of which the following is a specification, reference being had to the accompanying drawing, forming a part thereof.

Fig. 1 of the drawing is a perspective view of a combined oil burner casing and support therefor showing my new design;

Fig. 2 is a plan view of the combined oil burner casing and support therefor shown in Fig. 1;

Fig. 3 is a side elevation thereof; and

Fig. 4 is a partial rear elevation of the upper part of the same casing.

I claim:

The ornamental design for a combined oil burner casing and support therefor, substantially as shown.

MALCOLM R. KNOX.
